REAR VIEW MIRROR

Lynn Harold Hodge, 12618 Wyoming Ave.,
Detroit, Mich. 48238

Continuation-in-part of design application Ser. No.
17,288, May 23, 1969. This application Aug. 17,
1970, Ser. No. 24,531

Term of patent 3½ years

Int. Cl. D12—16
U.S. Cl. D14—6

FIG. 1 is a 3/4 front perspective view in closed position.

FIG. 2 is a 3/4 front perspective view in open position.

FIG. 3 is a 3/4 rear perspective view from below.

FIG. 4 is 3/4 rear perspective view from above.

FIG. 5 is a side elevational view.

This application is a continuation-in-part of my co-pending application Ser. No. D. 17,288, filed May 23, 1969, now abandoned.

I claim:

The ornamental design for a rear view mirror, substantially as shown and described.
